US0D1083584S

(12) **United States Design Patent** (10) **Patent No.:** **US D1,083,584 S**
(45) **Date of Patent:** **** Jul. 15, 2025**

(54) **PRODUCE CONTAINER**

(71) Applicant: **NS Brands, Ltd**, San Antonio, TX (US)

(72) Inventors: **Maria Elena Morales Hernández, Cuautitlán Izcalli (MX); Juan Gómez García, Jalisco (MX)**

(73) Assignee: **NS Brands, Ltd**, San Antonio, TX (US)

(**) Term: **15 Years**

(21) Appl. No.: **29/854,093**

(22) Filed: **Sep. 22, 2022**

(57) **CLAIM**

The ornamental design for a produce container, as shown and described.

DESCRIPTION

FIG. 1 is a perspective view for a produce container;

FIG. 2 is a side view thereof;

FIG. 3 is another side view thereof;

FIG. 4 is an end view thereof;

FIG. 5 is another end view thereof;

FIG. 6 is a top view thereof; and,

FIG. 7 is a bottom view thereof.

The broken lines in the drawings and the areas within them depict portions for a produce container that form no part of the claimed design.

1 Claim, 7 Drawing Sheets
